LATCHING DEVICE

John H. Sullivan, Los Angeles, Calif.

Application September 3, 1935, Serial No. 38,883

9 Claims. (Cl. 292—146)

This invention relates to a latching device applicable to various kinds of double closure members whether such members are swingably or slidably mounted. The invention also includes 5 a novel mechanical movement for locking devices which may be applied in other situations than that above mentioned.

An object of the invention is to provide an improved article of builders' hardware for the 10 purpose stated which will be simple in construction, inexpensive to manufacture and which will operate in a more efficient and satisfactory manner when applied to the doors and windows of dwellings, as well as when used in other situations.

One of the novel, improved features of the invention resides in the construction whereby the closing of one of a pair of cooperating doors, when the other door is already in the closed position will automatically lock both the doors in the closed position.

Referring to the accompanying drawing, which illustrates what is at present deemed to be a preferred embodiment of the invention,

Fig. 1 is a plan view of the latch casing and bolts.

Fig. 2 is a vertical section on line 2—2 of Fig. 3.

Fig. 3 is a section taken on line 3—3 of Fig. 2.

Fig. 4 is a cross section taken on line 4—4 of 30 Fig. 2.

Fig. 5 is a cross section taken on line 5—5 of Fig. 2.

Fig. 6 is a cross section taken on line 6—6 of Fig. 2.

Fig. 7 is a vertical section taken on line 7—7 of Fig. 8.

Fig. 8 is a front elevation partly broken away.

The embodiments of the invention which are shown, by way of example, in the drawing can 40 be manufactured in many different ways and out of a variety of preferred metals, for example cast iron, brass, bronze, or wrought steel. The device is easily installed, it being unnecessary to do any deep morticing or to bore any deep holes.

Referring in detail to the drawing, and describing first the form of the invention shown in Figs. 1 and 2, five sides of the lock casing are provided by means of the rectangularly shaped sheet metal member 5 which is fitted within a suitable recess made therefor in the wood work, the casing being completed by means of a face plate 6 having therein the bolt openings 7 and 8.

I term the bolt 9 the "friction" bolt and the bolt 10 the "sliding" bolt. Said bolts 9 and 10

cooperate with each other, their relative movements being controlled by means of a cross bolt 11. The sliding bolt 10 slides directly outwardly and inwardly with relation to the casing 5, but the friction bolt 9 has a tilting as well as a sliding movement.

The sliding bolt 10, has a flat face 10x on one side and a convexly beveled face 10b on the opposite side. The retraction of this bolt is effected when the closure member engages its 10 beveled face. The bifurcated portion 12 of the sliding bolt 10 has at its inner end reversely arranged bevels 13 and 14, and the adjacent end of the cross bolt 11 has reversely arranged bevels 15 and 16. The bevel 14 of the bolt 10 cooperates with the bevel 16 of the bolt 11 to force the latter bolt toward the friction bolt 9. When forced to the limit of its movement in the latter direction, the offset arm 17 with which the cross bolt is provided, beyond its adjoining shoulder 18, underlies the friction bolt 9 to prevent its retraction. Owing to the cross bolt being beveled both above at 16 and below at 15 it will operate 20 equally well either side up, and its offset arm 17 will always be positioned for thrusting under 25 a leg 12 of the sliding bolt 10.

Describing more in detail the cross bolt 11 it is shown as having two parallel bifurcations or limbs 20 and 21 which are spaced apart to fit 30 slidably within the lock casing. These limbs are respectively offset inwardly towards each other at 22 and 23 and are thus brought into engagement with each other to form the shoulder portion 18 already mentioned. The offset 22 is shorter than the offset 23 thus causing the shoulder portion 18 to be offset somewhat with relation to the midwidth of the lock casing. Owing to the bifurcated nature of the cross bolt the bevel 16 is of a two part character, and the same 40 is true of the bevel 15. Said cross bolt is furnished with a cross pin 24 which is located in a spaced relation to its bifurcated end and which bridges the space between the bifurcations thereof.

The friction bolt 9 is urged to its extended 45 position by means of a leaf spring 25 having a free end portion upon which said bolt seats. When said bolt is retracted against the opposition of said spring the spring undergoes both a torsional deflection and a longitudinal bending. Said 50 spring 25 has a downwardly curved end portion which is cut away at each side thus providing shoulders 26 and also providing at its midwidth a tail piece 27. Said shoulders prevent upward displacement of the cross bolt, and said tail piece 55

acts upon the cross pin 24 to move the cross bolt to its retracted position.

The friction bolt 9, as will be seen from Figs. 4 and 5, has at one side a short curved leg 30 and at its opposite side a longer straight leg 31, the outer surface of these legs fitting against the casing side walls with a working fit and forming the sides of a saddle-shaped construction whereby the bolt 9 is mounted upon the adjacent end portion of the spring 25. The concave inner side of the leg 30 grips the spring in such a way as to keep said spring and bolt in their proper operative relation. Said bolt at times undergoes a combined sliding and rocking or tilting movement thereof which results in its retraction, such a movement occurring when a closure member is forced against the flat surface 9x of the bolt as indicated by the arrow in Fig. 4. At such times the leaf spring 25 is subjected both to torsion and to a longitudinal bending, the position of the spring and the leg at such times being indicated by dotted lines in Fig. 4. During the retraction of the bolt its convexed and beveled face 9b slides across the adjacent edge of the bolt opening. Across the upper portion of the casing at about its midwidth extends a casing crosspin 32 around which is curled the upper part 33 of a leaf spring 34 which, as viewed in Fig. 2, is directed downwardly and towards the left to engage frictionally the upper surface of the cross bolt 11. The other leaf spring 25 fits snugly between the curl 33 and the under surface of the casing face plate 6.

The invention is illustrated as combined with a pair of swinging doors, or windows, 40 and 41, the lock casing 5 being embedded in the threshold 42 and door sill 43. When the door 41, which I term the "dead" door, is closed and bolted on the inside of the building, it will keep the sliding bolt 10 retracted and the cross bolt 11 will function to keep the other locking bolt 9 extended to lock the other closure member 40.

In operation this locking device acts automatically. Simply by opening or closing the sash or doors as the case may be, the standing leaf or dead door can be closed while the other door is open. Bolt 9 will act as a friction bolt and will hold the door closed, but it can be pulled or pushed open without great resistance. Simply closing the other door will push down the bolt 10 which by a cam action will slide the cross bolt 11 to lock the bolt 9, so that the dead door can not be opened until the other door has been opened first. However, if by chance the loose-leaf door should close first, as might be the case where door-closers are used, the standing-leaf can close after; in fact either door can close after, but the dead door positively can not be opened while the other door is closed. In other words the loose-leaf door operates the hardware without further assistance from anyone.

Molded, punched or forged parts may be used in constructing this locking device, and the shapes of the movable parts may be varied, within the scope of the claims, without departing from the spirit of the invention.

I claim:

1. In a latching device, a casing having a bolt opening, a bolt mounted within said casing and extensible through said opening by means of a combined rocking and sliding movement, and a spring mounted within said casing to extend said bolt, said bolt having a saddle portion furnished with limbs passing astride a free portion of said spring, said bolt also having a convexly beveled

face which slides across an edge of said bolt opening during the extension and retraction of the bolt.

2. The subject matter of claim 1 and, said spring being a leaf spring and at least one of said limbs of the bolt having a concave portion which fits around an edge portion of said spring. 5

3. In a latch, a casing, two latching bolts mounted in said casing in a spaced relation to each other, a bifurcated cross bolt operable by one of said latching bolts to at times prevent the retraction of the other latching bolt, a pin mounted on said cross bolt and bridging the bifurcation thereof, and a spring to retract said cross bolt, said spring acting against said pin. 10

4. In a latch, a casing, two latching bolts mounted in said casing in a spaced relation to each other, a cross bolt operable by one of said latching bolts to, at times, prevent the retraction of the other latching bolt, and a spring to retract said cross bolt, said cross bolt having two limbs extending in a spaced relation to each other and a cross pin connecting said limbs, and said spring having shoulders to engage said limbs and an arm or tongue between said shoulders to act against said pin in the retraction of said cross bolt. 20

5. In a latch, a casing, two latching bolts mounted in said casing in a spaced relation to each other, a cross bolt operable by one of said latching bolts to at times prevent the retraction of the other latching bolt, said casing having a face plate with openings through which said latching bolts are extensible, a cross pin in said casing near said face plate, and a bowed leaf spring underlying said face plate and held in an operative position between it and said pin, one end of said spring being in an operative relation to said cross bolt to retract it, and the other end being in an operative relation to one of said latching bolts to extend said latching bolt. 30

6. In a latch, a casing, two latching bolts in a spaced relation to each other within said casing and extensible therefrom into latching positions, one of said latching bolts having a bifurcation with two legs slidably fitting within said casing, 45 spring means tending to extend both of said latching bolts after their retraction, and a reversibly insertable cross bolt having an offset arm which is projectable under one or the other of the legs of said bifurcated bolt in whichever position said 50 cross bolt is inserted, said cross bolt being operable away from its normal position by the other latching bolt for movement into a latching relation with the bifurcated bolt, and a spring to restore said cross bolt to its normal position. 55

7. The subject matter of claim 6 and, said cross bolt having oppositely disposed beveled faces against either of which the latching bolt which actuates it may engage to move said cross bolt away from normal position, according to which of 60 said faces is placed uppermost when the cross bolt is inserted.

8. In a latch, a casing, a bolt mounted in said casing and having a combined sliding and tilting movement to and from a latching position, and a 65 leaf spring operatively related to said bolt, said spring undergoing a combined lateral bending and torsion about its axis when said bolt is retracted in opposition thereto, said bolt having a flat inner face and being provided with means which maintain said leaf spring in a flatwise contact with said face during the operation of the bolt. 70

9. In a latch, a casing, two latching bolts mounted in said casing in a spaced relation to 75

each other, and a slidable cross bolt mounted within said casing, one end portion of said cross bolt moving to and from a position wherein it obstructs the retraction of one of said latching bolts, and the other end portion of said cross bolt having a cam relation to the other latching bolt in order

to cause the retraction of the latter latching bolt to slide said cross bolt into the aforementioned bolt obstructing position, and means acting upon said cross bolt to return it to its nonobstructing position.
